UNITED STATES PATENT OFFICE.

LESLIE C. FRANK, OF WASHINGTON, DISTRICT OF COLUMBIA.

SEWAGE DISINFECTION.

1,141,050.

Specification of Letters Patent.

Patented May 25, 1915.

Application filed April 24, 1915. Serial No. 23,771.

(DEDICATED TO THE PUBLIC.)

To all whom it may concern:

Be it known that I, LESLIE C. FRANK, a citizen of the United States, and a resident of Washington, District of Columbia, have 5 invented a new and useful Improvement in Sewage Disinfection.

The invention herein described may be used by the Government or any of its officers, or employees, in prosecution of work 10 for the Government, or by any other person in the United States, without the payment of any royalty. (Act of March 3, 1883.)

The object of this invention is to provide an apparatus for disinfecting the sewage as 15 it is received directly from a toilet or closet.

The invention is specially designed to be used in connection with toilets or closets of railway coaches, or vessels.

The desirability of disinfecting the sewage 20 of vessels traveling in lanes as heavily frequented as those on the Great Lake system has been emphasized by the studies of Devalin (*Public Health Reports*, Vol. V) and of the International Joint Commission 25 on Boundary Waters. In these lanes of fresh water travel, within a very short time after one steamer has discharged toilet wastes, another steamer will pass over the same spot and take in drinking water. Furthermore, 30 these lanes of travel pass close by the drinking water intakes of a number of large cities. The present situation with regard to railways passing over water supply areas is even more serious. The dangers 35 of disease infection due to these conditions need no comment.

The process of disinfecting depends upon the bactericidal property of heat and is carried on by means of the apparatus 40 closed in the annexed drawing in which—

Figure 1 is a sectional view of one form of the apparatus; and Fig. 2 is a sectional view of a modified form of apparatus.

Referring to Fig. 1, the device is composed of: a chamber T insulated by some heat insulating material G such as the common magnesia cement, or sawdust; an influent pipe B penetrating nearly to the bottom of the tank; an effluent pipe A penetrating nearly to the bottom of the tank, and perforated at some point near the top of the tank by a small hole H about $\frac{1}{8}$ " in diameter; a steam pipe F provided with an ordinary straight-way valve E and a float C.

The lever handle of the straight-way valve 55 has been removed and replaced by a disk at the center of which is freely pivoted the lever arm of the float C, and which disk is provided with two pins, I and J, and a weighted member L for assisting to suddenly open or close the valve in a well known manner. X represents a drain through which sand and similar particles may be occasionally flushed.

The operation of this device is as follows: 60 Assume that the initial water level in the tank is at K. The steam valve E is in its closed position and the influent pipe B is submerged below the water level; in other words, the influent pipe B is always trapped, 65 even at the times of minimum water level in the tank. The entrance of sewage into the tank through B causes the level of water in the tank to rise gradually and to carry the float upward with it. The float arm, 70 however, is pivoted freely upon the steam valve disk and therefore does not turn on the steam by revolving the disk until it engages the pin I, i. e. until the liquid in the tank has reached a certain predetermined 75 height dependent upon the position of the pin I. When this height of water is reached the steam is suddenly turned on. For a time the entering steam is immediately condensed and gives up its heat to the water. 80 The water thus becomes heated at a rate dependent upon the rate and pressure of the steam discharge. As the temperature of the water approaches the boiling point the steam ceases condensing in the water, but rises 85 through the water and collects in the chamber space above it. At about the boiling point of water, or a trifle above, pressure develops in this upper space and gradually forces the sewage up and out through effluent pipe A. As the liquid discharges the 90 water-level and the float descends. The steam, however, remains turned on full until the float arm engages pin J, when a slight further descent shuts off the steam. The 100 level of liquid at which the steam is shut off, and at which discharge from the tank immediately ceases, may be predetermined by the position of the pin J. The small hole H is provided to enable the air in the tank to escape as the sewage enters. The relation 105 of the size of this hole to the total cross-section areas of the steam influent openings

is such that only a very small percentage of the steam entering through pipe F can escape through hole H, and therefore pressure develops in the tank practically as fast as if hole H were not present. This hole 5 may be replaced by a simple thermo-valve which will be open below say 80° C, and closed above that temperature, but the percentage of steam escaping through H is so 10 low that it is negligible.

It would be advisable that the steam supply to the device be closed while the train is standing in a passenger station to avoid the discharge of the contents at that time. 15 The steam supply valve stem can be made to penetrate the car floor external to the toilet room, and thus cause no more inconvenience in its operation than the present locking of the toilet doors. The disinfecter would have 20 a sufficient reserve capacity to care for the period of standing in stations. If the device be in the act of discharging as the station is approached the mere shutting off of the steam will at once discontinue the action. 25 Discharge will also cease immediately if the toilet be flushed and not begin again until the added material has been brought to the boiling point.

In the modified form of the apparatus, 30 shown in Fig. 2, the effluent pipe A' is made of sufficient length to insure the disinfection of the sewage at the temperature employed. This pipe is provided with an opening M near the bottom of the same for the entrance of the sewage. The pipe F', instead of terminating in the tank T as in Fig. 35 1, ends in an ejector nozzle O at the bottom

of the pipe A' in such a manner that the steam issuing from this nozzle, in passing by the opening M will draw in the sewage 40 contained in the tank T and eject the same through the pipe A'. The valve disk of the valve E is provided with a weighted member L so as to cause the valve E to open and close suddenly. In this form of the apparatus 45 the disinfecting action is due to the initial heating of the sewage as it enters the pipe A' and the continued heating as it passes up through the same. The length of the pipe A' should be such that the time 50 required for the sewage to pass through the same will be sufficient to kill all pathogenic organisms in the sewage. In the modification, when the sewage reaches a height determined by the position of the pin I the 55 weight member L will fall to the right, suddenly opening the valve E. The steam passing through the nozzle O will eject the sewage through the pipe A' at the same time thoroughly disintegrating the same so as to 60 expose all bacteria to the action of the steam. The nozzle O can be made large enough to admit sufficient steam to heat the sewage to any desired temperature.

I claim:—

Means for disinfecting sewage comprising a closed tank having inlet and outlet conduits opening into the lower part of the tank and the outlet pipe extending to a level above the tank, a pipe for conducting steam 70 into contact with the sewage, a float, and a valve in said pipe having a lost-motion connection with said float.

LESLIE C. FRANK.
